UNITED STATES PATENT OFFICE.

MICHAEL SPORLEDER, OF COLORADO CITY, COLORADO.

SAWING-MACHINE.

1,186,702.

Specification of Letters Patent. Patented June 13, 1916.

Application filed October 1, 1914. Serial No. 364,399.

To all whom it may concern:

Be it known that I, MICHAEL SPORLEDER, a citizen of the United States, residing at Colorado City, in the county of El Paso and State of Colorado, have invented certain new and useful Improvements in Sawing-Machines, of which the following is a specification.

My invention relates to improvements in sawing machines, and an object of my invention is the provision of means which can be instantly applied to and operated by a lathe, such as used by jewelers or watch makers.

Another object is the provision of a sawing machine which will be capable of instant application or removal; which will be small and compact in size to occupy a small space; and which will be simple and inexpensive in construction.

With these ends in view my invention consists of a sawing machine embodying novel features of construction and combination of parts for service, substantially as shown, described and claimed.

Figure 1 is a side view of my sawing machine applied to a lathe, Fig. 2 is a top plan view thereof, Fig. 3 is a view on line 3—3 of Fig. 1, Fig. 4 is a view on line 4—4 of Fig. 1, Fig. 5 is an enlarged sectional view of the means for guiding the saw carrying frame, and for holding the supporting frame in position and, Figs. 6, 7, and 8 are detail views of the mechanism shown in Fig. 5.

Referring by numerals to the drawings in which similar numerals denote corresponding parts in all of the views, the numeral 1 designates the lathe pedestal or support, 2 the table thereon, 3 the bearing bracket, on which is mounted the driving shaft 4; carrying the graduated grooved pulley 6; and the clutch 7 to retain a suitable tool or implement 8. These parts are of the usual construction employed in a jeweler's or watch maker's lathe and in connection with which I prefer to use my sawing machine.

The table is provided with a longitudinally disposed opening or passage 9, having formed thereon at its upper portion an enlarged passage 10, entering another longitudinally disposed opening or passage 11, having a beveled upper face 16 formed therein. Fitting in the opening 10, is the base 12, of the threaded sleeve 13, having a plurality of rounded corners formed thereon and which is first inserted in the said open-

ing 10, at one end of the table 2 and when at the desired location is then turned into locking engagement with the slot or opening 10, by means of a suitable tool co-operating with the grooves 17 formed in the upper end of the sleeve 13. This seats the guide sleeve 13, in the table, and the threaded sleeve 13, is engaged by the threaded collar 14, having openings 15, to receive a tool 65 for screwing the collar on the sleeve 13, thus substantially locking the said sleeve 13 and the frame 18 to the said table 2 as clearly illustrated by Fig. 5 of the accompanying drawings.

The construction described is clearly shown in Figs. 5, 6, 7, and 8, and provides a guiding sleeve which is locked in the lathe table and a clamping collar surrounding said sleeve, which collar after being 75 properly arranged will substantially clamp the said frame upon the lathe table.

The frame 18, is of L-shape having its vertical arm 18' provided with a collar 19, to receive the lower end of the upper L-shaped section 20, of the frame. The upper section 20 and lower section 18, are secured together by a suitable fastening 21, and said upper section is provided with a guide opening 22. In the sleeve 13, fits and 80 is guided the vertical arm 23, of the lower saw carrying member whose horizontal arm 23', is provided with a clamp 24, for securing the vertical arm 25, of the upper saw carrying member whose horizontal arm 25', 85 is provided at its free inner end with a threaded collar 26, forming the slot for the threaded lower end 27, of the sleeve 28. The sleeve 28, is guided in the opening 22, of the upper frame section and has a threaded 90 base 29, to be engaged by the adjusting bolt 30, which is operated by the winged nut 31, and the adjusting bolt at its lower end is formed with a head 32, receiving the jaws 95 of the upper saw clamps 33. The upper saw clamps 33, are thus carried by the adjusting bolt and the lower saw clamp 34, is secured to the lower frame section at 35, the saw 36, being thus clamped and retained by said clamps 33, and 34. Between the 100 upper and lower frame sections is arranged the work support or table 37, having the opening 38, to allow the passage of the saw, the segmental slot 39, to receive the upper saw frame section and having the annular portion 40, for attachment at 41, to the 105 lower frame section. Upon the lower frame

110

section is adjustably secured the collar 42, having an arm 43, connected to one end 44, of the link 45, whose other end 46, is connected to the crank 47 mounted on the driving shaft of the lathe.

The revolution of the driving shaft of the lathe imparts rotation to the crank, which by reason of its connection moves the saw frame rapidly up and down and effects the sawing operation.

The saw frame is properly guided and retained, the saw can be easily applied and removed as can also the entire machine, and generally from every point of view the invention will prove efficient and practical.

I claim:

1. In combination with the lathe table having an opening therein, a guide fitting in said opening, a lower L-shaped frame member having its horizontal arm clamped upon said guide, an upper L-shaped frame member adjustably connected to the lower frame member, a lower saw frame member adapted to reciprocate in said guide, an upper L-shaped saw frame member connected

to said lower member, a saw mounted in said saw frame members, and connections with the lathe for reciprocating the said saw frame.

2. In combination with the lathe table having an opening therein, a guide fitting in said opening, a lower L-shaped frame member having its horizontal arm clamped upon said guide, an upper L-shaped frame member adjustably connected to the lower frame member, a lower saw frame member adapted to reciprocate in said guide, an upper L-shaped saw frame member connected to said lower member, a saw mounted in said saw frame members, a work table support, a work table having adjustable connection with said support, and connections with the lathe for reciprocating the said saw frame.

In testimony whereof I affix my signature in presence of two witnesses.

MICHAEL SPORLEDER.
